UNITED STATES PATENT OFFICE.

MILTON H. WALLERSTEIN, OF PADUCAH, KENTUCKY.

DISPLAY-RACK.

1,380,856.

Specification of Letters Patent. Patented June 7, 1921.

Application filed February 18, 1920. Serial No. 359,528.

To all whom it may concern:

Be it known that I, MILTON H. WALLERSTEIN, a citizen of the United States, residing at Paducah, in the county of McCracken 5 and State of Kentucky, have invented certain new and useful Improvements in Display-Racks; and I do hereby declare the following to be a full, clear, and exact description of the invention, such as will enable 10 others skilled in the art to which it appertains to make and use the same.

This invention relates to improvements in what are commonly termed display racks, particularly designed for displaying or exhibiting advantageously to view goods or 15 articles of merchandise especially for salable purposes.

The invention has for its object to provide for readily suspending, within an 20 enclosure or casing preferably having a glass or transparent closure, wearing apparel either for men or women, especially in stores, for facilitating showing said apparel as in making sales.

25 A further object is to provide for compactly and with facility folding the rack out of the way when not employed for displaying purposes.

A still further object is to carry out these 30 ends in a simple, inexpensive and effective manner.

Other objects of the invention will be apparent from the following disclosure and accompanying illustration.

35 The invention consists therefore of certain instrumentalities and features of construction substantially as hereinafter more fully disclosed and defined by the appended claim.

The accompanying drawings illustrate 40 the preferred embodiment or one form of my invention wherein it will be understood that various changes and modifications as to the detailed construction and arrangement of parts may be made without departing 45 from the spirit or scope of my invention as covered by the claim.

In the drawings:

Figure 1 is a side elevation of my invention, parts being broken away, preferably 50 incased;

Fig. 2 is an end elevation of the same, parts also being removed, shown without the casing;

Fig. 3 is a fragmental, detail plan view;

55 Fig. 4 is a similar end view, both these latter views being on an enlarged scale;

Fig. 5 is a fragmental side view of a modification of my invention, showing the plurality of hanger-rods connected or coupled together to provide for the simultaneous 60 movement of such plurality of hanger-rods;

Fig. 6 is a fragmental end view, without the casing, of a further modification;

Fig. 7 is a vertical sectional view showing my invention as adapted to provide what 65 may be locally termed as a "floor" or "aisle" rack, the hanger or suspender bars being shown also in dotted lines as extended in both directions;

Fig. 8 is a side elevation of the same showing portions of the hanger or suspender bars adjusted angularly to the right and to the left, respectively, and others or intermediate ones occupying an initial position.

As characteristic features of my invention, I provide a suitable inclosure or casing 70 1 of any suitable material, the front being preferably of glass or transparent, for exhibiting or providing for the ready viewing of the displayed articles of apparel or clothing.

Within the casing or inclosure 1 is suitably secured or positioned opposite horizontal track-bars or rails 3, 3^a, reference being made, in this instance, to Fig. 1, the rails or 85 members of said track being of suitable material, steel or otherwise, said casing or inclosure being of suitable dimensions, as to height and otherwise, to provide for the suitable suspension of the articles therein. 90

A bar or beam 4 is portably supported upon, and transversely of the track-rails 3, 3^a, said transverse bar or beam being provided with rollers 5 carried by trucks 5^a, 5^b, said rollers being suitably journaled thereon 95 to occupy diagonally opposite positions above and below said track-rails, thus being adapted to contact with the upper and lower surfaces of said rails, respectively, as clearly shown in the several views. The diagonally 100 opposite corner edges of the trucks carrying the rollers are provided with projecting portions as 5^x, to allow said rollers to travel directly upon the track-rails, in front and rear of said trucks and not laterally thereof. 105

The transverse bar or beam 4 is to be made of any suitable material, but if made of wood it is to be reinforced or armored by the application thereto of a metallic plate (not shown) fitted down upon its upper 110 surface, and is provided with a plurality of suspender or hanger rods 6 upon which are

suspended the articles or wearing apparent, as now preferably practised or adopted especially in displaying a certain class of store, or made-up goods, particularly of the light type thereof. In using the device, it will be appreciated that it is only necessary, in order to obtain access to the inclosed suspended articles within the casing to grasp and draw upon any hanger rod until the same is pulled outwardly so that the desired garment may be conveniently withdrawn for examination and may be as readily replaced and returned within the casing to initial position thereafter. These hangers or suspending rods are bent at right angles at one of their ends, which right-angled portions enter vertical orifices 6^a in the beam or member 4, allowing them to be moved or adjusted angularly when desired.

In Fig. 5, I have shown an arrangement of several pluralities of hangers or suspender-rods 6^b, each of which pluralities, arranged one above the other, is connected together by a common rod or element 7 whereby by actuating any one of said elements 7 all of the transverse bars or beams may be moved along the track-rails outwardly, together with the respective pluralities of hanger or suspender rods, for the examination of any garment or article and thus obviate several operations, as would otherwise be required in effecting such examination.

In Figs. 7 and 8 is shown, as previously indicated, the device as adapted for what may be called floor or aisle use, including a case 1^a, a multiple of series or pluralities of hanger or suspender members 2^a, track-members 3 3^a, and transverse bars 2^b, the tracks 40 and their rollers being designated as 4 and 4^a, respectively. In this form of the invention, it will be observed that as the suspender members of the series one above another, are connected together, said hanger or suspender members, or any of these, may be drawn outwardly so as to be positioned at opposite sides of the case, in the aisle, for instance, as indicated in dotted lines at 3^c, for displaying particularly small articles, 50 for quickly providing for such display and facilitating the withdrawal of the hangers or suspender members.

Having described my invention, what I claim and desire to secure by Letters Patent is:

A device of the type described, including a plurality of transverse traveling members each provided with a plurality of hanger-members, means adapted to allow of the movement of said traveling members comprising trucks carrying the latter and adapted to provide for the attachment thereto of the said traveling-member, a hanger-member of each plurality thereof being connected together by a common member.

In testimony whereof, I affix my signature.

MILTON H. WALLERSTEIN.
